UNITED STATES PATENT OFFICE.

IRENÉE LECOEUR, OF DARNETAL, FRANCE.

MECHANISM FOR APPLYING POWER TO SEWING-MACHINES.

SPECIFICATION forming part of Letters Patent No. 254,225, dated February 28, 1882.

Application filed July 9, 1881. (No model.) Patented in France March 15, 1881.

To all whom it may concern:

Be it known that I, IRENÉE LECOEUR, a citizen of the Republic of France, residing at Darnetal, in the Department of Seine-Inférieure and Republic of France, have invented a new and useful Mechanism for Applying Power to Sewing-Machines, (for which I have obtained a patent in France, bearing date March 15, A. D. 1881, No. 141,696,) of which the following is a specification.

My invention relates to improvements in devices in which transmission of power from a main shaft to counter-shafts is effected by means of friction-wheels; and the objects of my improvements are, first, to provide a rotary disk transferring the power to the friction-wheel; and, second, to afford facilities for the radial motion of the friction-wheel on the face of the rotary disk, in order to vary the speed of the machine. I attain these objects by the mechanism illustrated in the accompanying drawings, in which—

Figure 1 is a side elevation of the mechanism applied to two sewing-machines, one opposite the other; Fig. 2, a front elevation, and Fig. 3 a plan thereof.

Similar letters refer to similar parts throughout the several views.

The bevel-wheel t' at the main shaft T drives the bevel-wheels a , the shafts of which rest in the cross-bearings t . A disk, A , being fixed on the other end of the shaft, rotates with a' and transfers the motion to the friction-wheel B , arranged at right angles to the disks A . The wheel B is mounted on the shaft b , provided with a square part, b' , whereon the wheel B can be displaced radially to the face of the disk A . The hole in the nave of B be-

ing square, too, and of the same size as the square part of b , the latter is turned in the same direction as the wheel B , and thereby drives the pulley P' , connected with the pulley P of the sewing-machine by the belt p . To displace the friction-wheel on the shaft b serves the mechanism, composed of the fork c'' , the treadle C , and the treadle-shaft C' . The fork c'' is fixed to the shaft C' , where also the treadle C is attached. So moving one side of the latter up or down, also the bifurcated end of the fork c'' is displaced horizontally, and because the pin b'' of the loose collar b''' , attached to the friction-wheel B , rests between the fork c'' , the wheel B is removed in horizontal direction nearer to or farther from the circumference of A . In consequence a corresponding speed is communicated to the wheel B and transferred to the pulley P' by the shaft b .

Having thus fully described my invention, what I desire to claim, and secure by Letters Patent, is—

In a device for applying a variable speed to sewing-machines, the combination of the disk A with the friction-wheel B , collar b''' , pin b'' , fork c'' , treadle-shaft C' , and treadle C , substantially as described, and for the purpose set forth.

In testimony whereof I have signed this specification in the presence of two subscribing witnesses.

I. LECOEUR.
